UNITED STATES PATENT OFFICE.

ARTHUR J. EVERE, OF CHICAGO, ILLINOIS.

BOX-MAKING MACHINE.

1,385,988.

Specification of Letters Patent.

Patented Aug. 2, 1921.

Application filed September 20, 1920. Serial No. 411,689.

To all whom it may concern:

Be it known that I, ARTHUR J. EVERE, a citizen of the United States, residing at Chicago, in the county of Cook and State of Illinois, have invented certain new and useful Improvements in Box-Making Machines, of which the following is a specification.

My invention relates generally to improvements in machines for automatically producing pasteboard and similar boxes or containers, and preferably, but not necessarily exclusively, to those made from a single pasteboard blank and having necks integral with the body portions of the boxes over which the covers are adapted to fit.

One of the leading aims of the present invention is the provision or production of a relatively simple machine of this kind which produces such boxes economically in rapid succession, the blanks being fed automatically and supplied with proper adhesive. Salient features of the machine are simplicity in structure, effectiveness in operation, speed of operation, unlikelihood of becoming injured or damaged in service, and the quality of the product which is manufactured.

To enable those skilled in this art to have a full and complete understanding of the invention and its various benefits and advantages, and the manner of attainment of the above-specified objects, I have illustrated a preferred and desirable embodiment of the invention in the accompanying drawings, forming a part of this specification and throughout the several views of which like reference characters refer to the same parts.

In these drawings—

Figure 1 is a plan view of the machine; Fig. 2 is a front elevation of the same;

Fig. 3 is an end elevation of the appliance;

Fig. 4 is a vertical section on an enlarged scale on line 4—4 of Fig. 1;

Fig. 5 is a vertical section at right-angles to the section of Fig. 4 on line 5—5 of Fig. 1;

Fig. 6 is a horizontal section on an enlarged scale on line 6—6 of Fig. 2;

Fig. 7 is a horizontal section on line 7—7 of Fig. 4 through the expandable and contractile rectangular form and its operating mechanism;

Fig. 8 is a horizontal section illustrating the means for supporting and guiding the sections of the contractile and expandible form;

Fig. 9 illustrates in perspective one of the

corner members associated with the sectional form;

Fig. 10 shows one of the form-section supports in perspective;

Fig. 11 is a transverse section on line 11—11 of Fig. 2;

Figs. 12 and 13 are details of the form and its spreading mechanism;

Fig. 14 shows one of the form elements in perspective;

Fig. 15 is a face view of one of the pasteboard blanks; and

Fig. 16 shows a fragment of one of the two-pronged elements which fold the ears or tabs around the corners of the form.

By reference to the drawings it will be seen that the machine includes a table 30 (Fig. 1) forming the top part of a supporting frame-work 31 having, as is usual, a plurality of legs resting on the floor. Bolted to the top of this table are two front standards 32, 32, and aligned rear standards 33, 33 (Figs. 1, 2, 5, and 6). A plate or casting 35, of the peculiar shape shown in Fig. 1, is mounted on the tops of the two front posts or standards 32, 32 and is held in position thereon by securing screws or bolts 34, 34.

Plate 35, as is shown perhaps most clearly in Fig. 5, has a central aperture 36 above which a U-shaped guide casting 37 is positioned, such element having a base 38 fastened to the top of plate 35 by securing screws 39 (see Figs. 1 and 5). In order to close the front of the rectangular passage of the member 37, the side flanges of the latter have a face plate 40 fastened thereto by screws 41, 41 (Figs. 1 and 5).

A rectangular block 42 is vertically reciprocated in the guide-member 37 and depending from the main body of the part 42 are ribs or wings 43, 44 at right angles to one another and with their lower edges somewhat beveled, such parts having further downward extensions or ribs 45, 46 thinner than the parts 43, 44 and with their lower edges slightly rounded off or beveled. Block 42 and its depending intersecting ribs or fins are centrally apertured for the accommodation of a cylindrical plug 47 having beveled or inclined surfaces 48 at its lower end (see Fig. 4).

Element 42 and its associated parts are reciprocated by a lever 49 (Fig. 3) fulcrumed at 50 on a bracket 51 mounted on the top of plate 35. One end of such lever is connected by a link 52 to the member 42, the other

end of the lever being united by a link 53 to a bar 54 vertically reciprocatory in guides in the frame-work and having a bifurcated end 55 (Fig. 2) equipped with a roller 56 traveling in the groove of a cam 57 on a shaft 58 revoluble in suitable bearings on the frame-work and provided near the back of the machine with a gear 59 in mesh with a pinion 60 on a drive-shaft 61 equipped at the front of the appliance with a hand-wheel 62 and at the rear with a drive-pulley, not shown. Obviously the rotation of shaft 61 is transmitted to shaft 58, and the cam 57 through the connecting means specified effects the vertical reciprocation of the angular-block 42 and its spreader means.

The expandible and contractible rectangular form about which the box-blank is folded to shape comprises the following co-operating instrumentalities. The under side of plate 35 is provided with four radiating pockets or sockets 70 (Fig. 7) having suitable bottom walls and side and end walls 71, 72, 73. Each of such pockets slidingly accommodates a bar 74 (Fig. 10) having a right-angle upstanding flange or rib 75 at one end, and each of these four flanges supports one of the like number of form-sections 76 secured thereto by screws 77. Each of the cavities or pockets 70 is equipped with a cover-plate 80 (Fig. 9) fixed in position by screws 81, and each such cover-plate has a depending portion fitted in the corresponding pocket and provided outside of the pocket with two vertically-spaced, inwardly-extended projections having right-angle faces 82 and 83 which act as stops or abutments for the flanges 75. Each member 80 inside of the pocket has a recess accommodating a portion of a coil spring 84, one end of which bears against the end wall of the recess, the other end pressing against the corresponding flange 75 tending to force that particular section of the form inwardly diagonally toward the common center of such form sections. It is to be understood that the rectangular form contracts by reason of the action of the springs 84 and expands because of the descent of the spreader described above acting to force the sections outwardly diagonally thereby enlarging its cross-sectional dimensions.

Referring more specifically to the peculiar or detailed construction of one of the form sections, as illustrated for example in Fig. 14, it will be observed that this member 76 has a lower slightly enlarged rectangular head 90 about which the body portion of the pasteboard blank 500 is bent and a section just above it cut away on its two outer sides at 95 and 96 providing a slightly-reduced portion on which the neck is formed to shape. It will also be observed that this form member is beveled along its two inner upper edges at 91 and 92 and along corre-

sponding shoulders at the neck portion of the element at 93 and 94. Additionally the inner longitudinal edge is cut away or chamfered at 97 for the accommodation of a portion of the plunger 47, terminating in an inclined or beveled face 98 with which one of the beveled surfaces 48 of the plunger is adapted to coöperate to spread or expand the form.

It will be readily understood that when the spreader block 42 and its form-spreading elements is elevated, as illustrated for example in Figs. 12 and 13, the form will be contracted by reason of the inward pushing action of the several diagonally-acting springs 84. When the spreader descends, however, the surfaces 48 coacting with the beveled faces 98, and the beveled edges of the parts 43 and 44 bearing on the inclined surfaces 91 and 92, and the lower edges of the parts 45 and 46 coöperating with the beveled faces 93 and 94, all act conjointly to spread or expand the rectangular form composed of the four parts ready for the bending or folding of the pasteboard blank 90 around it after which the spreader ascends, the form contracts, and the completed box is removed therefrom.

Referring now to the means for feeding the blanks in succession from a magazine to and bending them around the form, it will be seen that the machine comprises an upright magazine 100 (Figs. 1, 2, 3 and 6) adapted to accommodate a stack or pile of the blanks of suitable shape (Fig. 15) on which a weight may be superposed if desired. These blanks 500 are removed individually or one by one from the bottom of the magazine and fed to the form, and this feeding means comprises one or more brackets 101 supporting spaced, longitudinally-recessed guide-bars 102, 102 (Figs. 1 and 2) each accommodating a reciprocatory rack 103 (Figs. 2, 3 and 11) the teeth on the lower edges of which are in mesh with a gear 104 (Fig. 3) on a shaft 105 oscillatory in appropriate bearings 106 and 107. Shaft 105 is rocked by a pinion 108 (Fig. 2) thereon in mesh with a suitably-guided inclined rack 109 (slidable in an inclined bearing 110) secured to an arm 111 having a bifurcated end 112 straddling the shaft 58, and provided with an antifriction roller in the usual way coöperating with a cam 113 on shaft 58. By this simple means the companion, horizontal racks 103, 103 are reciprocated in proper timed relation to the operation of the other parts of the mechanism.

Two, parallel pusher-bars 120, 120 (Fig. 6) are fastened to and reciprocate with the racks 103, 103, such bars having shoulders 121, 121 (Fig. 1) near their rear ends adapted to engage the back edge of the lowermost pasteboard blank in the magazine and slide it forwardly toward the form. At their

front ends these two pushers have other shoulders, 122, 122 (Fig. 6) at a somewhat lower level and designed to feed the blanks during the latter portion of their travel beneath the form. 5 Adjacent to such pushers are two parallel, supporting plates, 123, 123 on which the traveling blank is supported and these are provided with flat leaf-springs 124, 124 beneath which the blank passes and 10 which act to hold it down in place on such supporting element 123. Side bars or gages 125, 125 are provided along the edges of the members 123 and extend a considerable distance therebeyond against which the ends 15 of the blanks bear to effect their proper travel and to prevent their displacement. The two reciprocatory racks 103, 103 have mounted thereon to slide therewith two, bent, supporting bars 126, 126 of the form and 20 style shown in Fig. 6 with downturned ends 127, 127 adapted to discharge the completed boxes from the machine, these elements 126 traveling beneath a pair of stationary guides or supporting plates 128, 128. 25 The appliance includes additionally two lower and upper, parallel, suitably-supported shafts 130 and 131 (Figs. 2 and 3) connected together by intermeshing gears 132 and 133, the lower shaft being longer than 30 its companion and provided with a sprocket-wheel 135 rotated by a chain 136 coöperating with a sprocket-wheel 137 on shaft 58, whereby the two shafts are rotated simultaneously in opposite directions. The lower 35 shaft 130 is equipped with a roller 129 (Fig. 6) fixed thereon and provided with a projecting finger 138, the upper shaft 131 being fitted with a mutilated or cut-away roller 134 (Fig. 1) coacting with such lower 40 roller to perform a part of the blank feeding operation. Shaft 130 is also fitted with two rollers and associated mechanism which applies the adhesive to the proper portions of the blank, which part of the mechanism 45 is not necessary here to describe since any suitable glue applying appliance may be used in this relation.

The operation of the blank-feeding mechanism occurs practically as follows:

50 The shoulders 121, 121 in traveling forwardly remove the lowermost pasteboard blank from the stack in the magazine pushing it along the supporting plates or bars 123, 123 between the side guides 125, 125 55 and beneath the leaf-springs 124, 124, and, at the proper moment, the larger or uncut-away part of roller 134 engages the front portion of the blank, and, by coöperating with the lower roller 129, the blank is fed 60 along having the adhesive applied thereto at the proper points at the same time. Practically as soon as roller 134 becomes inoperative on the blank because of its cutaway section, the finger 138 on the lower roller 65 129 pushes the blank forwardly slightly so

that it drops on to the two guides or supports 128 at a lower level. During the advancement of the blank by the turning of the coacting rollers 134 and 129, the racks 103, 103 are returning to original position 70 and practically as soon as the blank has been delivered by the finger 138 on to the members 128 the pushers 120 again advance, the supports 126 at the same time traveling with them and the shoulders 122 carry the 75 blank along the guides 128 and beyond their ends to the form, the blank at this time being supported solely on the traveling members 126. Such blank while thus supported is ready for bending or folding around the 80 form as will now be explained.

A rectangular bearing or guide 140 (Fig. 5) is secured by bolts or screws by means of its foot or lug 141 to the under side of the table, the bearing being located in an aperture through such table as is fully illustrated. Such vertical, guiding bearing accommodates a bar 142 rectangular in cross-section to fit the bearing and provided with a lower forked portion 143 straddling the 85 shaft 58 and equipped with a roller 144 traveling in the cam groove of a cam 145 on such shaft, whereby the rotation of the cam reciprocates the element 142 in a manner well understood. 95

Member 142 is provided with a central cylindrical cavity 146 accommodating a shorter slideable plunger 147 prevented from turning therein by means of a cross-pin 148 extended therethrough with its ends traveling in one or more slots 149 in the sides of element 142, such plunger being normally forced upwardly by a coil-spring 150 in the lower part of the cavity beneath the plunger, all as is fully shown in Figs. 4 and 5. At 100 its top end a rectangular block 151 is rigidly mounted on such plunger and is adapted to press the central portion 501 of the pasteboard-blank against the bottom of the sectional form. 110

To two of its opposite sides member 142 has pressure bars or blocks 160 (Fig. 5) pivoted thereto at 161, such members normally separating slightly by reason of the action of springs 162 in cavities in the elements 160 and bearing on the sides of the part 142. The extent which these pressure plates may separate is, of course, limited by their lower portions below the fulcrum pins 163 engaging the sides of the reciprocatory 115 element 142. At its opposite ends block 151 has two plates 153, 153 (Fig. 4) yieldingly held thereto by screws 154, 154 extended through apertures of the plates and mounted in threaded holes of the member 151, 120 springs 155 being interposed between the heads of the screws and the plates. 125

As will be readily perceived, when the member 142 ascends, the block 151 yieldingly presses the central part 501 of the 130

blank 500 against the bottom of the form and the four plates 153 and 160 bend up the sides 502 and ends 503 of the blank around the form, the member 142 continuing its upward movement after the block 151 has pressed the blank against the bottom of the form. By reason of the fact that the plates 153 are carried by the member 151 and the plate 160 by the element 142 the end flaps or wings 503 of the blank will be bent up to the form before the side wings or flaps 502 are folded up and this gives an opportunity, by mechanism described hereinafter, to fold or bend inwardly the body 15 and neck ears or tabs carried by the end wings against the form, so that when the side wings are bent up they will be outside of and caused to adhere to the outer faces of such ears.

20 Two levers 170 and 171 (Fig. 4) are fulcrumed at 172, 172, each carrying a bar 173 adapted to engage the neck portions 504 of the corresponding end wing or flap of the blank and press them against the reduced portion of the form, thereby forming a shoulder in the blank at the base of the neck all as is clearly depicted in Fig. 4. The lever 170 is operated by a bell-crank 174 fulcrumed co-axially with the lever and having an adjustable pressure-screw 177 adapted to bear on the outer face of lever 170, the two members 170 and 174 being normally yieldingly separated by means of a spring 180 accommodated in alined recesses in the two elements and surrounding a screw 178 fastened in the lever 170, projecting through an aperture of the bell-crank 174, and provided with one or more stop nuts 179.

40 In similar manner lever 171 is operated by another bell-crank 175 having a like connection therewith, the two bell-cranks being operatively connected by a link 176 assuring their simultaneous actuation.

45 Each of the bell-crank levers 174 and 175 at its opposite sides carries two leaf springs 181, 181 (Fig. 6) secured thereto by screws 182, 182, each spring at its free end having two spaced prongs 183 and 183^a (Fig. 16) of different thicknesses adapted to fold 50 against the form the ears or tabs 505 of the main portion 503 of the end pasteboard flaps or wings and the ears or tabs 506 of the crank portion 504 thereof. It is due to the fact that these ears are slightly offset in the completed box and the faces of the form against which they are bent are similarly offset that the prongs referred to are of different thicknesses.

60 Bell crank 174, and bell crank 175 through the connecting link 176, are operated through a link 184 (Fig. 4) connected thereto and to the upper end of a rod 185 vertically slideable in a bearing 186 and actuated by a cam 187 (Fig. 3) on shaft 58.

65 Two skeleton or frame levers 190, 190

(Fig. 5) are rockingly mounted on the table top at 191, 191, each carrying near its upper end a bar 193 adapted to shape the neck portion 507 of the side-wall wing of the pasteboard blank to the reduced-dimension section of the form, as is clearly illustrated. Each lever is additionally apertured for the reception of a slideable plunger 194 having an enlarged head 195 adapted to bear against the outer face of the corresponding pressure-plate 160, forcing the latter firmly against the body portion of the blank to press it against the side of the enlarged body section of the form. A spring 196 is interposed between each head 195 and its corresponding lever and the plunger is fitted with one or more stop-nuts 197 limiting the travel of the plunger in its aperture or bearing in the lever.

70 Each lever 190 is operated by a link 198 (Fig. 5) pivoted thereto at 199 and connecting it at 200 to ears 202 on a sleeve 203 supported on a shaft 201 mounted in the front and rear standards 32 and 33. The two sleeves are rocked by two cams 204 and 205 (Fig. 3) associated with rods 206 and 207 having two-branched portions straddling shaft 58 and pivotally connected at 208 and 209 (Fig. 5), respectively, with ears or lugs 210 on the sleeves, the rods or bars 206, 207 being equipped with yielding spring connections 211 of any suitable or appropriate type whereby the parts may yield slightly if subjected to undue pressure.

75 For the discharge or delivery of the 100 finished necked boxes a chute or guide 212 is mounted on a bracket 213 fastened to the table top.

80 Assuming that the flat blank has been brought under and in register with the form in the manner above described, member 142 rises and block 151 presses the part 501 of the blank against the bottom of the expanded form. Elements 153, 153 fold up the end parts 503, 504, 505 and 506 of the blank to 110 the form. Springs 181, 181 by means of their two prongs 183 and 183^a bend the tabs or ears 505 and 506 around the upright corners of the form. On the continued upward movement of member 142, plates 160, 160 115 bend up the side wings 502—507, whereupon such plates are firmly pressed toward the form by the plungers 194 and the four bars or blocks 173 and 193 press the neck parts 504 and 507 of the blank against the upper 120 reduced section of the form inwardly offsetting such portions of the blank and forming the neck on the box. The overlapped parts 502—505 and 507—506 having been supplied with glue or other adhesive while 125 the blank was flat, are caused to adhere together under such firm pressure and the box is completed. The form now contracts and is withdrawn upwardly out of the box, the various folders and pressers recede, and the 130

ends 127, 127 push the finished box out the discharge chute 212.

I claim:

1. In a machine for making necked pasteboard boxes, the combination of a shouldered form having a larger portion corresponding to the body of the box and a smaller portion corresponding to the neck of the box, means to bend the pasteboard blanks about the form, and means to press the blank to the reduced portion of the form to provide the neck in the box by offsetting the pasteboard at the shoulder of the form, substantially as described.

15 2. In a machine for making necked pasteboard boxes, the combination of a contractible and expansible shouldered form having a larger portion corresponding to the body of the box and a smaller portion corresponding to the neck of the box, means to contract and expand said form, means to bend the pasteboard blanks about the form, means to press the blank to the reduced portion of the form to provide the neck of the box by offsetting the pasteboard at the shoulder of the form, and means to remove the finished box from the form while the latter is contracted, substantially as described.

30 3. In a machine for making necked pasteboard boxes, the combination of a shouldered form having a larger portion corresponding to the body of the box and a smaller portion corresponding to the neck of the box, means to bend the end wall flaps of a pasteboard blank to the form, means to bend the ears of such flaps against the sides of the form, means to bend the side wall flaps of the blank against the form and said ears, and means to press the blank to the reduced portion of the form to provide the neck in the box by offsetting the pasteboard at the shoulder of the form, substantially as described.

45 4. In a machine for making necked pasteboard boxes, the combination of a contractible and expansible shouldered form having a larger portion corresponding to the body of the box and a smaller portion corresponding to the neck of the box, means to contract and expand said form, means to bend the end wall flaps of a pasteboard blank to the form, means to bend the ears of such flaps against the sides of the form, means to bend the side wall flaps of the blank against the form and said ears, and means to press the blank to the reduced portion of the form to provide the neck in the box by offsetting the pasteboard at the shoulder of the form, substantially as described.

50 5. In a machine for making necked pasteboard boxes, the combination of a shouldered form having a larger portion corresponding to the body of the box and a smaller portion corresponding to the neck of the box, means to bend the end wall flaps of a pasteboard blank to the form, means to bend the body

ears and separate neck ears of such flaps toward the opposite sides of the form, means to bend the side wall flaps of the blank to the form, means to press the body portions of said side wall flaps toward said body ears, 70 separate means to press the neck portions of said side wall flaps against said neck ears, and means to press the neck portions of the end wall flaps to the form, said two latter pressing means providing the neck portion 75 of the box by offsetting the pasteboard at the shoulder of the form, substantially as described.

6. In a box making machine of the character described, the combination of a sectional form composed of four corner pieces, springs tending to move such sections inwardly toward their common center, a spreader cross shape in cross-section adapted to slide between said form sections and expand them in opposition to the action of said springs, means to operate said spreader, and means to bend a pasteboard blank about the form, substantially as described.

7. In a box making machine of the character described, the combination of a sectional shouldered form composed of corner pieces, said form having a larger portion corresponding to the body of the box and a smaller portion corresponding to the neck 95 of the box, springs tending to move such form sections inwardly toward their common center, a spreader cross shape in cross-section adapted to slide between said form sections and expand them in opposition to the action of said springs, means to operate said spreader, means to bend a pasteboard blank about the form, and means to press the blank to the reduced portion of the form to provide the neck of the box by offsetting 105 the pasteboard at the shoulder of the form, substantially as described.

8. In a box making machine of the character described, the combination of a sectional shouldered form composed of four 110 corner pieces, said form having a larger portion corresponding to the body of the box and a smaller portion corresponding to the neck of the box, springs tending to move such sections inwardly toward their common 115 center, a spreader cross shape in cross-section adapted to slide between said form sections and expand them in opposition to the action of said springs, means to slide said spreader, means to bend the end wall flaps 120 of a pasteboard blank to the form, means to bend the ears of such end wall flaps toward the sides of the form, means to bend the side wall flaps of the blank against the form and said ears, and means to press the blank 125 to the reduced portion of the form to provide the neck in the box by offsetting the pasteboard at the shoulder of the form, substantially as described.

9. In a box-making machine of the char- 130

acter described, the combination of a plurality of horizontal diagonally-arranged pockets, supporting members slidable in said pockets toward and from a common center, 5 a vertically-disposed sectional form composed of corner pieces mounted on said supporting members, springs tending to move such form sections inwardly toward said common center, a vertical spreader adapted 10 to slide between said form sections, means to reciprocate said spreader to expand the form and permit its contraction, means to feed pasteboard blanks beneath the suspended form, means to bend the blanks about the form, and means to discharge the completed 15 boxes, substantially as described.

10. In a box-making machine of the character described, the combination of a plurality of horizontal diagonally-arranged

pockets, supporting members slidable in said 20 pockets toward and from a common center, a vertically-disposed sectional shouldered form composed of corner pieces mounted on said supporting members, springs tending to move said form sections inwardly toward said common center, a vertical spreader cross 25 shape in cross-section adapted to slide between said form sections, means to vertically reciprocate said spreader to expand the form and permit its contraction, means to feed 30 pasteboard blanks beneath the suspended form, means to bend the pasteboard blanks about the form, and means to press the blank to the reduced portion of the form to provide necks in the boxes by offsetting the 35 pasteboard at the shoulder of the form, substantially as described.

ARTHUR J. EVERSON.
